[57] CLAIM

[**] Term: 14 Years

The ornamental design for a stackable modular storage tower assembly of selectable height, as shown and described.

[21] Appl. No.: 27,318

DESCRIPTION

[22] Filed: Aug. 18, 1994

FIG. 1 is an isometric view of the right and front sides of a stackable modular storage tower assembly of selectable height showing our new design;

[63] Continuation-in-part of Ser. No. 198,630, Feb. 18, 1994.

FIG. 2 is an isometric view of the top left and front sides thereof;

[52] U.S. Cl. D14/102

FIGS. 3 and 4 are respective right side and left side elevation views thereof; and,

[58] Field of Search D14/100, 102,

FIG. 5 is a rear elevation thereof.

D14/107-109; D13/162, 184, 199; D6/421,

The undisclosed bottom view is unornamented except for the inclusion of the rectangular element shown in the views.

422, 423, 432, 396; 312/194, 208.1, 223.2,

223.3; 360/97.01, 97.04, 98.01, 99.01, 99.12;

361/600, 622, 724-728
